UNITED STATES PATENT OFFICE.

WILLIAM B. CHAPMAN, OF NEW YORK, N. Y.

GAS-WASHER.

992,706.

Specification of Letters Patent. Patented May 16, 1911.

Application filed March 5, 1910. Serial No. 547,516.

To all whom it may concern:

Be it known that I, WILLIAM B. CHAPMAN, of the borough of Manhattan, city, county, and State of New York, have invented certain new and useful Improvements in Gas-Washers, of which the following is a full, clear, and exact specification, such as will enable others skilled in the art to which it appertains to make and use the same.

My invention relates to an apparatus for removing tar and other impurities from producer gas by which such gas may be rendered clean and fit to be used for power purposes. To such apparatus it is essential that a thorough and violent contact between the gas and the water used for washing be brought about, thus driving from the gas and precipitating the tar and other bituminous content held in suspension in the gas.

My present invention therefore resides in certain features of construction and combination of parts which bring about this intimate and violent association of the water and gas and thoroughly expel the tarry matter and other impurities. All of this will be fully brought out hereinafter and the novel features particularly pointed out in the claims. For this purpose reference is now had to the accompanying drawings which represent, as an example, the preferred embodiment of my invention.

In such drawings; Figure 1 is a vertical section; Fig. 2 is a horizontal section on the line 2--2 of Fig. 1; and Fig. 3 is a plan view.

The apparatus has a casing preferably constructed of sheet metal and comprising an upwardly flaring body part 10 of circular cross-section, surmounted by a cylindrical collar 11 which in turn carries the circular blowing casing 12 having a tangentially disposed outlet nozzle 14.

15 indicates a collar which is adapted to be attached to a supporting element (not shown). Above this collar runs a collar 16 which has a bearing on the collar 15 and which is attached to a vertical shaft 17 extending downward through a stuffing box 18 on top of the blower housing 12 and through the housing 10 to a point near the bottom thereof. Between the stuffing box 18 and collar 15 is a pulley 19, which is attached to the shaft 17 and furnishes a means for driving the same.

Within the housing 10 is a circular baffle plate 20 having an opening 21 in the center thereof through which the shaft 17 passes. The bottom of the casing 12 has a central opening 22 therein through which the shaft 17 also passes. The shaft 17 carries at its lower end in the lower part of the housing 10 vertical, radial fan blades 23 fastened to the shaft by means of arms 24 and a hub 25. Fastened to the upper edges of these blades is a circular baffle plate 26 which turns with the blades and which carries at its periphery a number of down-stroking splashes 27. These are preferably formed of sheet metal with their projecting portions twisted or feathered so that when rotated in the direction indicated in the drawings they will have a down splashing effect on the water and a down-stroking action on the gas.

In the upper part of the housing 10 above the baffle 20 are arranged a second set of vertical radial fan blades 28 fastened to turn with the shaft 17 by arms 29 and a hub 30. At their upper edges the fan blades 28 carry a circular baffle plate 31 which rotates with them and which itself carries vertical radial blades 32 also rotating.

Within the housing 12 and fastened to the shaft 17 is a centrifugal, high pressure blower 33 which draws the gas through the orifice 22 and forces it out through the tangential nozzle 14.

A drain pipe 34 leads from the outlet 14 back into the collar 11 and housing 10 allowing any moisture in the outlet 14 to return to the washer proper. 37 indicates a water supply pipe which encircles the upper part of the housing 10 and, as shown in Fig. 2, has a number of connections 35 passing into the upper part of the housing 10 and turned so that they discharge the water in the direction of revolution of the shaft 17 and its attachments.

36 indicates baffle ribs which are spirally disposed and fastened to the interior walls of the housing 10 above and below the central wall 20. These baffles are so arranged relatively to the direction of rotation of the fans that below the partition or wall 20 the swirling gas and water are caused to flow upward along the baffle ribs, while above such walls the baffle ribs cause a down-flow of these elements. This, it will be seen, causes the water and gas to be thrown back upon themselves, thereby increasing the

agitation and confusion within the washer upon which its successful operation depends.

The operation of the apparatus may be traced as follows: The gas is supplied to the lower part of the housing 10 and streams of water are introduced through the nozzles 35. The shaft 17 is rotated at a high speed with the result that the blower 33 draws the gas rapidly into the housing 12. However, in passing through the housing 10 the gas first encounters the blades 23 and takes up the rotation thereof, so that it is thrown out to the sides of the housing 10 by centrifugal force. As it rises it is again baffled by the splashes 27 and it encounters the water falling through the housing 10. This water is also swirled around by the rotation of the blades 23 and this brings it into violent contact with the gas, both the water and gas being forced against each other and moving in opposite directions. The gas then passes through the opening 21 and again encounters the water in a violent splashing motion caused by the blades 28 and 32 and the baffle 31. In this manner the gas is again subjected to the violent and intimate association with the water as described. In the end the gas reaches the housing 12 and is discharged. In this way the tarry and bituminous matter is driven from the gas and the gas is cleansed. The agitation above-described is enhanced by the inclined baffle ribs 36 which, as has been described, are fastened to the walls of the housing 10 and are inclined in such a manner that they, the direction of rotation being fixed, stroke up and down against each other or rather cause the water and gas when moving in a circular path, to flow upward along the lower walls of the housing and downward along the upper walls. It will further be observed that the centrifugal action of the fans 28 and 32 tends to throw outward the tar, water and other solid matter, while the exhauster 33 pulls the gas inward against this tendency. This brings about an effectual separation of the gas from the solid matter in suspension therein.

Having thus described my invention what I claim as new and desire to secure by Letters Patent of the United States, is:

1. A gas washer, having a housing with a gas inlet at one end, an outlet at the other, an exhauster at the outlet, a water supply and means for baffling and swirling the gas and water comprising a fan, a baffle attached to and rotating therewith and inclined splashes carried by and projecting from the baffle.
2. A gas washer having a housing, a water supply, means for pulling the gas through the housing against the water flow therein, a fan operating within the housing, a baffle attached to and rotating with the fan and additional fan plates fastened to

the baffle at the side opposite the first-named fan.

3. A gas washer having a housing with a gas inlet and outlet, a water supply, means for pulling the gas through the housing contrary to the direction of the water flow, means for swirling the gas and water in the housing and inclined baffle ribs attached to the interior walls of the housing.

4. A gas washer having a housing with a gas inlet and outlet, a water supply, means for pulling the gas through the housing contrary to the direction of the water flow, means for swirling the gas and water in the housing and inclined baffle ribs attached to the interior walls of the housing, said baffle ribs being disposed with regard to the direction of the swirling motion to cause an up and down or reverse flow of the gas and water.

5. A gas washer having a housing with a gas inlet and outlet, a water supply, means for pulling the gas through the housing in direction contrary to the water flow, a fan in the housing, a baffle plate attached to the fan and splashes projecting out from the periphery of the plate.

6. A gas washer having a housing with a gas inlet and outlet, a water supply, means for pulling the gas through the housing in direction contrary to the water flow, a fan in the housing, a baffle plate attached to the fan and splashes projecting out from the periphery of the plate, said splashes being inclined or feathered so as to exert a tendency to throw the gas and water opposite the direction of the gas flow.

7. A gas washer comprising a housing with a gas inlet and outlet, a water supply, means for pulling the gas through the housing in direction contrary to the direction of water flow, an intermediate baffle plate in the housing, a fan at one side of the baffle plate, a baffle plate attached to the fan, a second fan in the housing at the second side of the first-named baffle plate, a baffle plate secured to and rotating with the second fan, and spiral baffle ribs attached to the inner wall of the housing and disposed with respect to the direction of the rotation of the fans to cause a flow of the swirling gas and water in direction toward the gas outlet.

8. A gas washer having a housing with a gas inlet at one end, an outlet at the other end, means for pulling the gas through the housing, a water supply and means for baffling and swirling the gas and water, said means including a baffle plate rotating substantially in its own plane and inclined splashes carried by and projecting from the baffle plate.

9. A gas washer having a housing with a gas inlet at one end, an outlet at the other, an exhauster at the outlet, a water supply and means for baffling and swirling the gas

and water, said means including a baffle plate and inclined splashes carried by and projecting from said plate.

10. A gas washer having a housing with a gas inlet and outlet, a water supply, means for causing the gas to pass through the housing in a direction contrary to the water flow, a baffle plate within said housing and splashes projecting from the periphery 10 of the plate, said baffle plate being rotatable and said splashes being inclined or

feathered so as to exert a tendency to throw the gas and water in a direction opposite to the direction of the gas flow.

In testimony whereof I have signed my name to this specification in the presence of two subscribing witnesses.
